CLAIM

The ornamental design for a crossbody bag as shown and described.

DESCRIPTION

FIG. 1 is a front-side perspective view of a crossbody bag. FIG. 2 is a front view of the crossbody bag of FIG. 1 thereof. FIG. 3 is a rear view of the crossbody bag.

FIG. 4 is a left-side view of a crossbody bag thereof.

FIG. 5 is a right-side view of a crossbody bag thereof.

FIG. 6 is a top view of a crossbody bag thereof.

FIG. 7 is a bottom view of a crossbody bag thereof; and, FIG. 8 is a view of the crossbody bag of FIG. 1 in another position of use.

The broken lines in the drawings represent stitching that forms part of the claimed design.
